INTERNAL COMBUSTION ENGINE

Asa B. Carmichael, Grand Coulee, Wash.

Application August 19, 1938, Serial No. 225,804

7 Claims. (Cl. 123—24)

This invention appertains to new and useful improvements in internal combustion engines and to engines which utilize as fuel other than liquids.

5 The principal object of the present invention is to provide an engine wherein the fuel consists in the discharging of a powdered explosive or dry explosive in the combustion chambers of the engine.

10 Another important object of the invention is to provide an engine wherein fuel is in the form of a tape carrying a multiplicity of deposits of explosive material which are rapidly set off in the combustion chambers of the engine.

15 Other objects and advantages of the invention will become apparent to the reader of the following specification.

In the drawings:

20 Figure 1 represents a front elevational view of the engine with parts in sections.

Figure 2 is a vertical sectional view through one of the cylinders.

Figure 3 is a horizontal sectional view through one of the cylinders and magazine.

25 Figure 4 is a fragmentary front elevational view with the turbine removed.

Figure 5 is a fragmentary detailed sectional view showing the ratchet means.

Figure 6 is a fragmentary plan view of the 30 explosive tape.

Figure 7 is a fragmentary detailed sectional view taken substantially on the line 7—7 of Figure 1.

Figure 8 is a fragmentary detailed sectional 35 view taken substantially on the line 8—8 of Figure 1.

Figure 9 is a perspective view of the firing pin mechanism.

Figure 10 is an end elevational view of the 40 magazine body.

Figure 11 is a fragmentary vertical sectional view through the magazine.

Referring to the drawings wherein like numerals designate like parts, it can be seen that 45 numeral 5 represents a cylinder block in which a piston 6 operates and this piston is connected in the usual way by a pitman 7 to a crankshaft 8 and in carrying out the present invention a crankshaft 8 has a gear 9 driving a smaller gear 10 on a cam shaft 11 with the cam thereof operating against a slide member 12 which controls a vertical rod 13 operating against a bell-crank 14 which in turn control an exhaust valve 15 which is normally closed by spring means 16.

55 Only one cylinder is shown in the drawings,

but of course each cylinder is equipped in the same manner as shown in the drawings.

Numeral 17 represents the head having a combustion chamber 18 and this head is provided with a laterally extending portion 19 which has a recess therein in the form of a pocket 20 in which a block 21 is slidable. Dovetailed connections 22 are provided between the sides of block 21 and the side walls of head extension 19. The block 21 has a reduced nose portion 23 formed by tapering the block 21 and across this is feedable a tape 24, this tape 24 having perforations along the longitudinal edges thereof denoted by numeral 25 for receiving pins 26 of a feed wheel 27 and carrying at equal spaced intervals deposits 28 of explosive material which are connected with caps 29 set off by percussion. These deposits and caps are assembled and suitably adhered to the tape 25 and are fed across the nose portion 23 of the block 21 by the feed mechanism. Each time a cap 29 is fired and the adjacent explosive deposit 28 set off, the block 21 is retracted so that another explosive deposit can be fed into position so that its cap 29 will be in a position to be struck by a firing pin 30 which operates through an opening 31 adjacent the extremity of the reduced portion 23. This firing pin 30 has a spring 32 associated therewith for projecting the same toward the cap and its outer end is formed with the 30 upstanding leg 33 with which the inner end of a rockable arm 34 is engageable. This arm 34 extends into a slot 35 of block 21 and through a slot in head extension 19 to terminate at its outer end within the path of a projection 36 carried by a disk 37, which disk is provided with a few peripheral teeth 38 meshable with rack teeth 39 on a plate extension 40 which projects laterally from the lower portion of the block 21 and through a slot in the lower portion of the head extension 19. Numeral 41 represents a housing for a turbine 42 and this turbine drives by a shaft 43. Extending to the housing 41 is a conduit 44 which extends from an air pressure cylinder 45. The lower end of the conduit 44 has an enlarged formation 46 in which is located a control valve 47 operative by the arm 48 and this arm is connected by a rod 49 to a suitable control within reach of the driver. In the mid-portion of the cylinder 45 is a partition 50 having a check valve 51 therein and in the cylinder below the partition 50 operates a piston 52 which is connected by a pitman 53 to cranks 54 on the aforementioned cam shaft 11. Numeral 55 represents an air intake check 55

valve, while numeral 56 represents an excessive pressure bleed valve. Numeral 57 represents a valve by which the storage chamber 58 can be charged or primed in the event pressure is completely spent therefrom. The purpose of the air cylinder 45 and turbine 42 is to provide drive means for the shaft 43 and gear 37 for feeding the tape 24 and operating the firing pin 30. The air compressor 52, storage tank 58 and turbine 42 are employed for driving the shaft 43, pin 36 and toothed disk 37, to the end that motive force is supplied for operating the block 21 and firing pin operating arm 34.

A shell-like structure 60 is formed with a slip connection 61 for the upper end of the head extension 19 and this flares out to form two cases 62 for pay-off and take-on reels 63 and 64 which are mounted on stub shafts 65 in the said shells 62. The tape 24 extends from the reel 63 and is fed by a wheel 27 with the co-operation of a roller 66 mounted opposedly thereto. The tape extends longitudinally inwardly and outwardly of the block 21 to return to the take-on reel 64. Obviously at each revolution of the shaft 43 the firing pin 31 is cocked and subsequently gear 37 operating on the rack 39 will hold block 21 so that the tape 24 is held clamped between the reduced nose 23 of the abutment block 21 and the cylinder block 18 pending releasement of the firing pin 31 by the rocker 34.

The feed wheel 27 is operated as is apparent in Figure 11. The feed wheel 27 is mounted on a shaft 71 which operates through a bushing 72 and which at its lower end carries a ratchet wheel 73. Swingable or rotatable on the shaft 71 is an arm 74 which carries a pawl 75 (spring-pressed) and obviously each time cam formation 76 on the adjacent side of disk 37 strikes the same the resulting motion is imparted to feed wheel 27.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In an internal combustion engine, a combustion chamber, a tape carrying deposits of explosive material, means for feeding the tape to the combustion chamber and means for firing the explosive deposits successively at the firing chamber, said means for firing the explosive deposits consisting of a firing pin and automatic means for operating the pin, said means for feeding the tape being controlled by the operation of the engine, a fluid operated turbine controlled by the operation of the engine and being adapted to operate the feed mechanism and firing means simultaneously.

2. In an internal combustion engine, a combustion chamber, a tape carrying deposits of explosive material, means for feeding the tape to firing position at the combustion chamber, means for firing the explosive deposits successively at the firing chamber, a rotor driven by the engine, said means for firing the explosive deposits consisting of a retractile spring projected firing pin, and means between the rotor and the firing pin for retracting and releasing the pin intermittently, said last-mentioned

means consisting of an arm rotated by the rotor and a rocker having one end engageable with the firing pin and the other end by the arm.

3. In an internal combustion engine, a combustion chamber, a tape carrying deposits of explosive material, means for feeding the tape to firing position at the combustion chamber, means for firing the explosive deposits successively at the firing chamber, a rotor driven by the engine, said means for firing the explosive deposits consisting of a retractile spring projected firing pin, and means between the rotor and the firing pin for retracting and releasing the pin intermittently, and a slidale abutment over which the tape travels.

4. In an internal combustion engine, a combustion chamber, a tape carrying deposits of explosive material, means for feeding the tape to firing position at the combustion chamber, means for firing the explosive deposits successively at the firing chamber, a rotor driven by the engine, said means for firing the explosive deposits consisting of a retractile spring projected firing pin, and means between the rotor and the firing pin for retracting and releasing the pin intermittently, and a slidale abutment over which the tape travels, and holding means operative by the said rotor for clamping the abutment against the tape and closing the combustion chamber when an explosive deposit is being discharged.

5. In an internal combustion engine, a combustion chamber, a tape carrying deposits of explosive material, means for feeding the tape to firing position at the combustion chamber, means for firing the explosive deposits successively at the firing chamber, a rotor driven by the engine, said means for firing the explosive deposits consisting of a retractile spring projected firing pin, and means between the rotor and the firing pin for retracting and releasing the pin intermittently, said means for feeding the tape comprising a roll engaging the tape, a ratchet wheel, a pawl rockably mounted and adapted to drive the ratchet wheel and a boss on the rotor for engaging the rockable pawl and operating the ratchet wheel, said ratchet wheel being rotatable with the rotor.

6. In an internal combustion engine, a combustion chamber, a tape carrying deposits of explosive material, means for feeding the tape to firing position at the combustion chamber, means for firing the explosive deposits successively at the firing chamber, a rotor driven by the engine, said means for firing the explosive deposits consisting of a retractile spring projected firing pin, and means between the rotor and the firing pin for retracting and releasing the pin intermittently, an abutment movable against the tape to hold the same in proper position at the combustion chamber, and means carried by the rotor for holding the abutment in tape clamping position at the time releasement of the firing pin takes place.

7. In an internal combustion engine, a feedable tape, explosive deposits arranged on the tape at equal spaced intervals, firing means for the explosive deposits, feed means for the tape, said feed means including a turbine, a fluid compressing means, a conduit from the fluid compressing means to the turbine and a control for the passage of compressed fluid in the conduit.

ASA B. CARMICHAEL.
